UNITED STATES PATENT OFFICE.

RUDOLPH KROLL, OF SPEARFISH, SOUTH DAKOTA.

REFRIGERATOR.

No. 821,650.

Specification of Letters Patent.

Patented May 29, 1906.

Application filed June 13, 1905. Serial No. 265,083.

To all whom it may concern:

Be it known that I, RUDOLPH KROLL, a citizen of the United States, residing at Spearfish, in the county of Lawrence and State of 5 South Dakota, have invented certain new and useful Improvements in Refrigerators, of which the following is a specification.

This invention relates to refrigerators, and more particularly to that type which are used 10 by merchants and others having large quantities of provisions which must be kept cool.

In refrigerators as commonly constructed much difficulty and annoyance is experienced in hoisting and packing the ice in the ice- 15 chamber. As designed by me the ice-chamber is preferably placed in the cellar or basement immediately below the provision-chamber. This has the double advantage of allowing the ice-supply to be easily placed in position 20 and also keeping moisture away from the provisions.

The object of this invention is to produce a device of this character which will be very effective in operation, which will consume a 25 minimum amount of ice, and which can be cheaply constructed.

For a full description of the invention and the merits thereof, and also to acquire a knowledge of the details of construction of 30 the means for effecting the result, reference is to be had to the following description and accompanying drawing, which is a vertical sectional view through the refrigerator as constructed by me.

35 Corresponding and like parts are referred to in the following description and indicated in all the views of the drawing by the same reference characters.

The numeral 1 designates the wall which 40 surrounds the ice-chamber and which is preferably made of masonry, so as to exclude heat to as great an extent as possible. Wall- plates 2 are placed thereon and a floor 3 built in the usual manner. The provision-chamber 45 5 is built upon these wall-plates and the sides thereof comprise two spaced partitions 5, having an air-space 6 between them. Since air is a non-conducting medium, the ex-

ternal heat is thus kept out of the provision-chamber. An air-inlet 7 is located in the 50 ice-chamber, and the air, after entering through this inlet, passes upward around the ice and through perforations 8 in the floor, and finally emerges through a flue 9 in the upper chamber 4. Since the colder and 55 denser air will be at the bottom of the ice-chamber, it may be desirable to draw the air into the provision-chamber through pipes 10, which extend from the floor 3 to the bottom of the lower chamber, and are preferably located opposite to the air-inlet 7. A drainage-pipe 11 is so located as to carry away the water as quickly as the ice melts. In order to insure the desired circulation of air, it may be found necessary to employ artificial means, 60 such as a fan 12, located in the flue 9.

It will thus be understood that I have invented a refrigerator in which the provision-chamber will be entirely free from moisture and in which the ice can be very conveniently 70 placed in position.

Having thus described the invention, what is claimed as new is—

An ice-house comprising non-heat-conducting sides and a roof, a perforated floor 75 dividing the ice-house into a lower compartment which is used as an ice-chamber and an upper compartment which is used as a provision-chamber, the ice-chamber being located beneath the surface of the ground, an 80 air-inlet pipe leading into one side of the ice-chamber at a point near the bottom thereof, a series of pipes extending from the floor to the lower portion of the ice-chamber and located diametrically opposite to the air-inlet 85 pipe, an air-outlet pipe leading from the upper portion of the provision-chamber, and a fan located in said pipe and adapted to produce a circulation of air from the ice-chamber to the provision-chamber. 90

In testimony whereof I affix my signature in presence of two witnesses.

RUDOLPH KROLL. [L. S.]
